CURTAIN TIE-BACK DESIGN HOLDER

Dudley A. Huber, Calico Rock, Ark.

Application October 9, 1936, Serial No. 104,843

6 Claims. (Cl. 156—33)

This invention relates to a tie-back holding device for window curtains or drapes.

The principal object of this invention is to provide a tie-back holding device formed of stiff wire and adjustably mounted on a supporting bracket for attachment to a door or window frame.

Another object of this invention relates to the formation of the wire tie-back holding device as a U-shaped element one arm of which is adjustably mounted on its supporting bracket and the other arm of which is provided with a plurality of parallel sections arranged to slidably receive an ornamental element.

15 A further object of the invention relates to the manner of detachably mounting such an ornamental element to the tie-back holder whereby the same may be easily and quickly replaced by an ornamental element of a different character.

20 A still further object of the invention relates to the construction of the ornamental element.

Other objects and advantages of the invention relate to various improved details of construction and novel arrangements of the parts as will 25 be more fully set forth in the detailed description to follow:

Referring to the drawing:—

Fig. 1 is a front elevational view of the tie-back holding device without its ornamental design, shown attached to the side of a window frame.

30 Fig. 2 is a plan view of the tie-back holding device with ornamental design attached taken on line 2—2, Fig. 1.

Fig. 3 is an end view of the tie-back holding device and attached ornamental design.

35 Fig. 4 is a rear elevational view of the attached ornamental design and the arm of the tie-back holding device supporting the same taken on line 4—4, Fig. 3.

40 In the embodiment of the invention illustrated herewith, 10 generally denotes the tie-back holding device shown attached to a side of a window frame 11 on which is hung a curtain or drape 12 shown in dotted lines.

45 The tie-back holding device is preferably formed of a stiff wire bent U-shaped to define a rear arm 13 and a front arm 14, which may be made of a length slightly in excess of the length of the rear arm. The free end of the rear arm 13 terminates in an eye 15 arranged to be mounted on the threaded stud 16 projecting from a supporting bracket 17. As will be observed, the front and rear arms 13 and 14 are parallel and are disposed in a horizontal plane with the curved

connecting portion 18 extending in a direction towards the center of the window.

Carrying the threaded stud 16, as above mentioned, is a supporting bracket 17 which is formed of sheet metal provided along its outside edge 5 with a rearwardly directed right-angle flange 19 adapted to engage the outside edge 20 of the window frame 11. A screw 21, securely attaches the bracket 17 to the window frame 11. To securely lock the eye 15 of the rear arm 13 to the bracket 17, there is provided a washer element 22 and nut 23 on the threaded stud 16. It will thus be seen that this construction provides for a ready angular adjustment of the tie-back holding device 10 on its supporting bracket 17 relative to the window frame 11.

Arranged on the front arm 14 and in the same vertical plane therewith are the fingers or sections 24 and 25 formed of the same stiff wire as used in the arms 13 and 14. The sections 24 and 25 may constitute the arms of a U-shaped element, the bowed portion 26 of which is welded or otherwise secured to the main front arm 14 as at 27, in such a manner as to equally space the sections 24 and 25 from the main front arm 14. 25 Preferably the ends of the sections 24 and 25 terminate in vertical registry with the end of the main front arm 14, as clearly shown in Figs. 1 and 4.

Adapted for attachment to the front arm 14 is 30 an ornamental element 30 which may be of any desired size, shape, color and configuration and which may also be of any desired metallic or non-metallic material. Preferably I contemplate forming the ornamental element 30 of a plastic 35 material, and embedded in the back thereof are the eyelets 31, one for each of the sections 24 and 25, and one for the main front arm 14. Referring to Fig. 4, it will be seen that the eyelets 31 are arranged at each of the ends of the ornamental element 30. While only three eyelets 31 are shown, it is to be understood that any desired number may be utilized in any desired arrangement.

45 The ornamental element 30 is attached to the tie-back holding device 10 by the simple expedient of sliding the sections 24 and 25 and front arm 14 through the appropriate eyelets 31. The size of the ornamental element should be such as to completely hide from view the arm 14 and the sections 24 and 25.

50 When the assembled unit is attached to a window or door frame the curtain or drape is held back by simply placing the same between the 55

arms 13 and 14 of the tie-back holding device, in the manner readily apparent.

Having thus set forth and disclosed the nature of this invention, what is claimed is:

- 5 1. A tie-back holding device for curtains comprising a unitary rigid supporting bracket adapted for permanent attachment to a frame, a U-shaped holding element comprising a rear arm and a front arm, adjustable means mounting the 10 free end of the rear arm to said supporting bracket, spaced rod sections on said front arm, an ornamental element, and means on said ornamental element arranged for slidable coaction with said spaced rod sections and said front arm 15 providing a readily attachable and detachable medium for said ornamental element on said holding element.
- 20 2. A tie-back holding device for curtains comprising an L-shaped supporting bracket for attachment to a frame with both legs thereof arranged in abutting relation to the front side and one side edge of said frame, a U-shaped holding element formed of stiff wire comprising a rear arm and a front arm, an eye provided at the 25 free end of the rear arm, a threaded stud on the front face of said supporting bracket for mounting said eye including a nut for adjustably clamping said holding element to said bracket, spaced rod sections on said front arm arranged in the 30 vertical plane thereof, an ornamental element, and a plurality of eyelets fixed to back of said ornamental element and arranged for slidable coaction with said spaced rod sections and said front arm whereby said ornamental element may 35 be readily attachable and detachable.
- 40 3. A tie-back holding device for curtains comprising an L-shaped supporting bracket for attachment to a frame with both legs thereof arranged in abutting relation to the front side and one side edge of said frame, a U-shaped holding element formed of stiff wire comprising a rear arm and a front arm, an eye provided at the free 45 end of the rear arm, a threaded stud on the front face of said supporting bracket for mounting said eye including a nut for adjustably clamping said holding element to said bracket, spaced rod sections on said front arm arranged in the vertical plane thereof, an ornamental element, a plurality of eyelets fixed to back of said ornamental ele-

ment and arranged for slidable coaction with said spaced rod sections and said front arm whereby said ornamental element may be readily attachable and detachable, and said front arm being of a length greater than said rear arm, and said spaced rod sections being arranged above and below and co-extensive with said front arm, the terminal ends of said spaced rod sections being substantially in vertical registry with the terminal end of said front arm.

5 10 4. A tie-back holding device for curtains comprising an L-shaped supporting bracket for attachment to a frame with both legs thereof arranged in abutting relation to the front side and one side edge of said frame, a U-shaped holding element formed of stiff wire comprising a rear arm and a front arm, an eye provided at the free 15 end of the rear arm, a threaded stud on the front face of said supporting bracket for mounting said eye including a nut for adjustably clamping said 20 holding element to said bracket, spaced rod sections on said front arm arranged in the vertical plane thereof, an ornamental element, a plurality of eyelets fixed to back of said ornamental element and arranged for slidable coaction with 25 said spaced rod sections and said front arm whereby said ornamental element may be readily attachable and detachable, and said ornamental element being of such a size and configuration as to completely cover said spaced rod sections and 30 at least the major portion of said front arm.

5 35 5. A holding element for a tie-back holding device comprising a U-shaped member formed of a stiff wire and defining a rear arm and a front arm, an attaching eye formed at the free end of the rear arm, upper and lower coextensive rod sections arranged parallel to and in the vertical plane of said front arm, the inner ends of said sections being fixedly secured to said front arm, and the outer ends of said sections being substantially 40 in vertical registry with the terminal end of said front arm.

6. An ornamental element for a tie-back holding device comprising a body portion, and a plurality of spaced eyelets fixedly attached to the back of said body portion for slidably mounting 45 said element on said tie-back holding device.

DUDLEY A. HUBER.
